UNITED STATES PATENT OFFICE

HARRY J. LEBHERZ, OF FREDERICK, MARYLAND, ASSIGNOR TO THE EVEREDY COMPANY, OF FREDERICK, MARYLAND, A CORPORATION OF MARYLAND

BOTTLE CAPPER

Application filed August 27, 1927. Serial No. 215,926.

My invention relates broadly to bottle capping tools and more particularly to a construction of double rack and geared rider type of bottle capper for placing crown caps upon bottles.

5 One of the objects of my invention is to provide a hand operated double rack bottle capping machine which will be more reliable in its operation than hand operated bottle cappers heretofore available.

10 Another object of my invention is to provide a construction of manually operated double rack bottle capper in which a relatively large force may be exerted in effecting a bottle capping operation for a relatively small force impressed upon a manually operated lever device.

15 Still another object of my invention is to provide a construction of bottle capper wherein a rider is mounted for vertical slideable movement with respect to a double rack with independent gears arranged to mesh with the double rack and to mutually intermesh for translating a downward movement 20 on the hand operated lever into a bottle capping operation with spring means arranged to return the hand operated lever to its normal position after each bottle capping operation.

25 30 A further object of my invention is to provide an assembly of multiple gears arranged interiorly of a slideable rider on a double rack with a connection between one of the gears and a hand operated lever for controlling the movement of the gears and the elevation of the rider with respect to the double rack in effecting successive bottle capping operations.

35 40 A still further object of my invention resides in the construction of a rider and gear system for a double rack bottle capper having spring means for returning the rider to a bottle capping position after successive bottle capping operations.

45 50 A still further object of my invention is to provide a construction of crown cap guide and multiple feed device which is carried by the rider intermediate a double rack structure for insuring a successive supply

of crown caps to bottles for each capping operation.

Other and further objects of my invention reside in the construction of a double rack bottle capping tool and arrangement of parts thereof, as more fully described in the specification hereinafter following, by reference to the accompanying drawings in which:

55 60 Figure 1 illustrates a side elevational view of the double rack bottle capper of my invention; Fig. 2 is an end view of the bottle capping tool of my invention; Fig. 3 is a cross-sectional view taken through the rider of the double rack bottle capping tool of my invention; Fig. 4 is a cross-sectional view through the rider of the capping tool on the line 4—4 of Fig. 3; Fig. 5 is a fragmentary cross-sectional view through the spring return mechanism on line 5—5 of Fig. 3; Fig. 6 is a fragmentary view illustrating the cap feeding and guiding device which is carried by the rider of the bottle capping tool of my invention; and Fig. 7 is a view of the double rack and rider construction showing the operating gears and hand operated lever moved to a position where the rider may be adjusted to a selected elevation along the double rack structure for capping bottles of different sizes or heights.

65 70 75 80 In my Letters Patent Reissue No. 15,285 dated February 14, 1922 I have described a construction of hand operated rack and gear mechanism for bottle capping tools. In my copending applications, Ser. No. 755,672, filed Dec. 13, 1924; Ser. No. 69,868, filed Nov. 18, 1925; Ser. No. 158,908, filed Jan. 4, 1927; Ser. No. 106,696, filed Feb. 8, 1927; and Ser. No. 213,404, filed August 16, 1927, I have shown various features of a rack and gear hand operated bottle capping tool.

85 90 95 100 My present invention is an improvement over said Letters Patent and the structures illustrated in said copending applications. In the bottle capper of my present invention I provide a double rack system with a rider which engages the double rack system and is moved with respect thereto by means of a system of cooperating gears which are actuated by means of a hand le-

ver for effecting a downward movement of the rider during a bottle capping operation, insuring a return of the hand operated lever to normal position after successive bottle capping operations. By movement of the gears to a position out of engagement with the racks the rider may be moved to a selected position with respect to the base of the bottle capper to permit operation of the capper with bottles of different sizes or heights. The rider is arranged to carry a device for insuring a multiple feed of crown caps to bottles. Special provision is made for journaling the system of gears within the rider and reducing wearing of the relatively thin pressed metal parts under conditions of rough usage and long operation.

Referring to the drawings in more detail reference character 1 represents a pressed metal base which carries at opposite ends thereof the standards 2 and 3. The standard 2 has a rack member 4 adjacent its upper extremity and standard 3 has a rack member 5 facing or directed toward the rack member 4. Slidable rider 6 is formed from sheet metal shaped at the ends to slidably embrace the standards 2 and 3. The rider 6 forms a substantially rectangular box-like closer surrounding the standards 2 and 3 with substantially T-shape portions 7 which embrace the standards and form a sliding guider or track. The rider 6 has a rivet member 8 passing therethrough on which is journaled the mutilated gear or toothed segment 9. The sides of the rider 6 are apertured at 10 for receiving disc members 11 in each side thereof, the disc members 11 being rotatable in the apertures 10 in the nature of bearings. Hand lever 12 is provided with bifurcated portions 14 which extend on opposite sides of the rider 6 and connect by means of rivet members 15 through bearing members 11 with mutilated gear or toothed segment 16 which is arranged to mesh with the mutilated gear or toothed segment 9 and with the rack 4. The mutilated gear or segment 16 is provided with a notch 17 in which a cross-arm 18 is seated under the action of spring members 19 and 20. The spiral springs 19 and 20 are anchored at their lower extremities to the lower portion of rider 6 as represented at 21. The cross-arm 18 may be moved in an arcuate slot 22 during the actuation of the bottle capper, and serves at all times to exert a continuous force on the segment 16 tending to roll the segment in a counter-clockwise direction for elevating the lever 12 to normal bottle capping position after each successive operation. The segments 16 and 9 roll together upon the racks 4 and 5, respectively, under the action of spring members 19 and 20 in returning the rider to an elevated position after each successive bottle capping

operation. The rider 6 carries the capping throat 23 in a position intermediate the standards 2 and 3, and adjacent the capping throat 23 I provide a guide 24 for the crown caps which may be fed along the track member 25 or chute which is arranged to be secured to the guide 24.

The arrangement of the bearing members 11 in the apertures 10 formed in the side plates of the rider 6 avoids the wearing away of the material of the rider during the continued bottle capping operations as the journal members 11 slide upon the surfaces of the apertures 10 without injury to the rider.

I have found the bottle capper construction illustrated herein extremely practical and desirable from the viewpoint of manufacture and production and efficient in its use in bottle capping operations.

While I have described my invention in one of its preferred embodiments, I desire that it be understood that modifications may be made and that no limitations upon my invention are intended other than those imposed by the scope of the appended claims.

What I claim as new and desire to secure by Letters Patent of the United States is as follows:

1. A bottle capper comprising a pair of standards, racks formed on the extremities of said standards, a rider slidably mounted on said standards, cooperatively related gear members journaled in said rider and meshing with said racks, said gear members being mutually intermeshed and housed within said rider between said standards in a plane passing through said racks, a capping throat carried by said rider for impressing a crown cap upon a bottle located between said standards, an actuating lever connected to one of said gear members and spring means engaged by one of said gear members for constantly urging said gear members into a position in which said actuating lever is normally in an elevated position.

2. A bottle capper comprising a pair of standards, racks formed on the upper extremities of said standards and directed toward each other, a rider slidably mounted on said racks, a pair of gear members journaled in said rider and meshing with each other and with said racks, a spring device extending through said rider and engaging one of said gear members for elevating said rider to a predetermined bottle capping position, a hand actuating lever connected with said gear members and a bottle capping throat carried by said rider for impressing a crown cap upon a bottle positioned between said standards upon successive operations of said hand actuating lever.

3. A bottle capper comprising a pair of standards, racks formed on the upper ex-

tremities of said standards, a rider slidably mounted upon said racks and having arcuate shaped slots extending through the sides thereof, a pair of gear devices rotatably journaled on said rider and meshing with each other and with said racks, a hand operating lever connected with one of said gear devices, a bridge member extending through the arcuate shaped slots in said rider and spring means connected with said bridge member for normally urging said bridge member into abutment with one of said gear devices for maintaining said hand operating lever in normally elevated position for effecting successive bottle capping operations and a capper throat carried by said rider for impressing a crown cap upon a bottle positioned between said standards.

In testimony whereof I affix my signature.

HARRY J. LEBHERZ.
